UNITED STATES PATENT OFFICE

SEYMOUR TROY, OF NEW YORK, N. Y.

DESIGN FOR A WOMAN'S SHOE

Application filed April 9, 1931. Serial No. 39,408. Term of patent 14 years.

To all whom it may concern:

Be it known that I, SEYMOUR TROY, a citizen of the Republic of Poland, residing at New York, county and State of New York, have invented a new, original, and ornamental Design for a Woman's Shoe, of which the following is a specification, reference being had to the accompanying drawing, forming a part thereof.

Figure 1 is a side view of a woman's shoe showing my new design, the essential features of which are shown in full lines. Figure 2 is a top front perspective view of the same. In Figure 2 the shoe shown has been foreshortened in the drawing.

I claim:

The ornamental design for a woman's shoe substantially as shown and described.

SEYMOUR TROY.
